D. W. FEITEL

CLEANING APPARATUS

Filed April 6, 1926

UNITED STATES PATENT OFFICE.

DANIEL W. REITEE, OF BROOKLYN, NEW YORK.

CLEANING APPARATUS.

Application filed April 6, 1926. Serial No. 100,075.

This invention relates to a cleaning apparatus.

The object of the invention is the production of an apparatus, by means of which 5 different objects, such as pieces of fabric, carpets, bags of various kinds, namely cement bags, plaster bags, flour bags and the like can be economically and quickly cleaned. The second object of the invention is the production of a cleaning apparatus, wherewith 10 the dust, dirt or other material dusted from the bags or other objects is easily collected. The third object of the invention is the production of a cleaning apparatus with a cleaning 15 drum constructed to tumble the objects dusted therein without the use of baffle plates.

The organization of the invention comprises a dust tight housing having a door for an opening therein. A rotatable hollow 20 drum is located in the housing and has provided therefor a charging door and discharging door for suitable openings thereof. A dust collecting hopper is located below the housing, and is provided with a door for 25 an opening thereof which coacts with the discharging door of the drum to form a discharge chute for said drum.

In the accompanying drawings, Fig. 1 represents a vertical section of an exemplification 30 of the apparatus, as on the line I—I of Fig. 2; Fig. 2 shows a partial right hand side view partly broken away of Fig. 1 and a partial section of Fig. 1 on the line 2—2; Fig. 3 indicates a left hand view of Fig. 2, 35 and Fig. 4 shows a partial sectional view similar to Fig. 2 on a reduced scale with a modification.

A floor or platform 20 is indicated with the opening 21, and has supported thereon 40 a dust tight housing designated in its entirety by the letter A, and comprises the front wall 25, the rear wall 26 and the side walls 27 and 28. A roof or cover 30 is provided for said walls. A pair of hinged doors 31 are provided for an opening in the front wall 25. A pair of bolts 32 maintain the doors 31 in locked position. A cleaning 45 drum designated in its entirety by the letter B, is located within the housing A, and comprises the end walls 35, which in this instance are hexagonal, but may be of other contour. The said walls 35 are mortised at their corners for the triangular shaped longitudinal braces 36. The braces 36 are mortised for the cross slats 37 at right angles thereto and longitudinal slats 38 at right

angles to said slats 37 bear upon and are fastened to the slats 37, forming lattice work having the small rectangular dust openings 40. The lattice work having the dust openings 40, maintains the material operated upon within the drum while rotating. The braces 36 with the lattice work form longitudinal flat walls of the drum B. A charging door 43 is hinged over an opening in one of the 60 longitudinal walls of the drum, and is provided with a bolt 44, to lock it in its closed position. A discharging door 45 is hinged over an opening 46 in one of the longitudinal walls of the drum, by means of the hinges 70 47 and bolts 48 are provided to maintain the door 45 in its locked position.

Disc flanges 53 have extending therefrom the trunnions 55. The flanges 53 bear on the outer faces of the end walls 35. Supplemental discs 56 bear against the inner faces of the end walls 35, and bolts 57 extend through the flanges 53, the discs 56 and the walls 35 to clamp the said flanges 53, and the supplemental disc 56 to the said 80 walls 35.

Journal brackets 58 are supported on the floor 20 and have journaled therein the trunnions 55. One of the latter is provided with the tight pulley 60 and the loose pulley 61 65 for the belt 62.

Straps 63 extend from the disc flanges 53, to which they are secured by the bolts 57, and extend to and over one of each pair of braces 36, to which they are fastened by the bolts 90 65. Shorter straps 66 extend from and are fastened to the outer faces of the end walls 35, and are bent over the accompanying brace 36 of each pair and are fastened to the latter by means of the bolts 67.

A dust collecting hopper is designated in its entirety by the letter C and comprises the front tapering wall 68 having the door opening 69, the rear tapering wall 70, and the side tapering walls 71 and 72. The walls 100 of the hopper C have connected thereto the dust outlet chute 73. A plate valve 74 is guided in grooves 75 of the chute 73, and guide plates 76 extend from said chute for the valve 74. Hooks 77 extend from the 105 chute 73 for the detachable dust collecting bag 78.

A hopper door 80 is hinged to the wall 68 of the hopper C, by means of the hinges 81. A stop 82 extends from the lower face of the 110 floor 20 outside of said hopper, for the door 80, and a stop 83 in the hopper has its ends

fastened to the walls 71 and 72 thereof for said door 80.

To use the dust cleaning apparatus, the doors 31 are opened, and the cleaning drum 5 B is brought to the position indicated in the drawings with the door 43 located in a vertical plane. The door 43 is then swung open, the discharging door 45 being in its closed position. The objects to be cleaned are then 10 located in the drum B and the doors 31 and 43 are closed. The drum is next rotated, by means of the belt 62, and the objects therein are thereby tumbled against the lattice work of the longitudinal walls thereof, and the dust 15 and foreign matter are discharged and escape through the openings 40 and enter the hopper C. The dust then enters the chute 73, above the valve 74. During the rotations of the drum B the door 80 of the hopper is located in its closed position as indicated in 20 Figs. 2 and 3. After the objects in the drum are cleaned, the drum B is stopped, and the valve 74 is moved to its open position. The dust collected in said hopper then drops into 25 the bag 78, in which it is collected. Next the operator swings the door 80 of the hopper C so that its free end bears against the stop 83, and the door 45 of drum B is swung to its 30 open position bearing on the door 80, as shown in Fig. 1. In this location of the doors 45 and 80 they form a discharge chute for the bags or other contents of the drum, which then drop from the drum through the opening 46, slide on the doors 45 and 80 and are 35 discharged through the opening 69.

The door 43 and its opening may be dispensed with and the drum may be charged as well as discharged through the opening 46 having the door 45. The longitudinal flat 40 walls of the drum B provide practical means for tumbling the objects operated upon without the use of baffle plates.

Referring to the modification shown in Fig. 4, the floor is again shown at 20, with its 45 opening 21. The dust tight housing A is again indicated with its front wall 25, the rear wall 26, one of its side walls 27, its roof 30 and doors 31. The cleaning drum similar to B is indicated in its entirety by the letter B'. The charging door 43 of the drum is omitted, and in place of the single discharging door 45 there is substituted the main discharging door 90 which is hinged over an

opening similar to 46, not shown, in one of the longitudinal walls of the drum, by means 55 of the hinges 47. The door 90 has hinged thereto for an opening therein, the supplemental door 91, which functions as a charging door for the drum B'.

The hopper is again indicated in its entirety by the letter C, with the wall 68 having the opening 69, the wall 70, the door 80, the stops 82 and 83. The dust outlet chute for the hopper is again indicated at 73 with its valve 74.

To use the modified form of the invention indicated in Fig. 4, and to charge its drum B', the latter is brought to the position indicated in said Fig. 4 with the doors 31 opened, and the door 90 in its closed position. The supplemental door 91 is then opened and the objects to be operated upon are located within the drum. The supplemental door 91 is next closed and the drum rotated in the usual manner with the door 80 of the hopper in its closed position. After the contents of the drum B' have been cleaned the said drum is again brought to the position shown in Fig. 4, and the door 90 is opened and brought to bear on the door 80, but the door 91 is kept 80 closed. In this position of the parts the contents of the drum B' will drop therefrom and be discharged through the opening 69.

Various modifications may be made in the invention and the present exemplification is 85 to be taken as illustrative and not limitative thereof.

Having described my invention what I desire to secure by Letters Patent and claim is:

In an apparatus of the character described 90 the combination of a housing, a door for an opening in the housing, a cleaning drum trunnioned in the housing, said drum comprising end walls, flat longitudinal walls supported on and fastened to the end walls, said 95 flat walls comprising longitudinal braces and cross slats at right angles thereto forming lattice work with small dust discharge openings and maintaining the objects operated upon in said drums during its rotation, a 100 charging door hinged over an opening in one of said longitudinal walls and a discharging door over an opening in one of the other longitudinal walls of the drum.

In testimony whereof I affix my signature.

DANIEL W. FEITEL.
